UNITED STATES PATENT OFFICE.

WALTER ALEXANDER WILSON AND SYDNEY WILSON, OF VANCOUVER, BRITISH COLUMBIA, CANADA.

STREET INDICATOR.

Application filed July 15, 1921. Serial No. 484,984.

To all whom it may concern:

Be it known that we, WALTER ALEXANDER WILSON and SYDNEY WILSON, both subjects of the King of Great Britain, and both residents of the city of Vancouver, in the Province of British Columbia, Canada, have invented certain new and useful Improvements in Street Indicators, of which the following is a specification.

10 Our invention relates to improvements in street indicators, and the object of our invention is to provide a device adapted for installation in street cars by means of which the names of the streets past which the car 15 travels may be indicated in a simple manner to the passengers prior to the arrival of the car thereat, and which device is simple in construction and operation, requiring the minimum amount of attention on the part of 20 the operator since it is provided with a positive stopping and spacing means whereby the movement of the band on which the street names are displayed is automatically controlled.

25 We attain this object by the construction illustrated in the accompanying drawings in which—

Fig. 1 is a face view of the device.

Fig. 2 is a view of the mechanism.

30 Fig. 3 is a sectional elevation taken through line 3—3 of Fig. 2.

Fig. 4 is a detail view in part section of a band roller.

Fig. 5 is a fragmentary view of one end of 35 a band roller.

Fig. 6 is a partial view of the gear shifting mechanism.

Fig. 7 is an end view of Fig. 6.

Fig. 8 is an end view showing the contact 40 arm and ring.

Fig. 9 is a side view of Fig. 8.

Fig. 10 is a detail view of the spacing roller stop pin.

45 Fig. 11 is a diagrammatic view of the circuit wiring.

Fig. 12 is a detail view of the brake drum and band.

Similar figures of reference indicate similar parts throughout the several views.

50 The device consists of a casing 1, formed of any suitable material and of any preferred shape, having one side provided with a display opening 2. Rotatably mounted within the casing adjacent its upper and 55 lower ends are upper and lower rollers 3

and 4 respectively to which the ends of a band or ribbon 5 are secured and on which the ribbon may be wound by the rotation of the rollers, the rotation being effected by means of a suitably mounted shaft 6 60 provided with bevel gears 7 and 8 adapted to mesh with bevel gears 9 and 10 detachably connected to the rollers 3 and 4. These gears are connected to the rollers as shown more particularly in Fig. 4, that is, the 65 roller, indicated by the numeral 3, is mounted rotatably on a shaft 11 which extends through a bearing 12 secured to the casing 1 on one side, being held stationary in the bearing by means of a set screw 13, and at 70 its opposite end this shaft is formed as a needle-point bearing 14 and engages a complementary recess 15 formed in the inner end of a short length of shaft 16 to which the bevel gear 9 is secured by a set screw 17, 75 mounted on this shaft is a sleeve 18 the inner end of which is provided with a slot 19 adapted to slidably engage an integral key 20 formed on the end of the roller 3 and this sleeve is rotatably mounted in a 80 bearing 21 secured to the casing on the side opposite to bearing 12 and is secured to the shaft 16 by means of a set screw 22 passed through a collar 23 into the shaft, from which it will be seen that rotation of the 85 bevel gear 9 rotates shaft 16 and sleeve 18 and consequently the roller 3, but that the roller may be removed from place by removing the set screw 13, enabling the shaft 11 to be withdrawn and the roller taken out so 90 that another roller may be substituted when required. For the easy withdrawal of shaft 11 it is provided with a gripping pin 24. The foregoing description applies to the 95 construction of the lower roller 4.

As the gears 7 and 8 mesh alternately with the gears 9 and 10 that is, one set of gears is used for driving the mechanism in one direction and the other set for driving it in the opposite direction the shaft 6 is mounted 100 for longitudinal movement and is operated to carry the gears 7 and 8 into or out of mesh respectively with gears 9 and 10 by any suitable mechanism, such as the rack and pinion mechanism, indicated respectively by 105 the numerals 25 and 26 in Figs. 2, 6 and 7, the rack being connected to the shaft 6 and the pinion being operated by means of a rod 27 connected to a lever 28 secured to the end of the shaft on which the pinion is 110

mounted, so that by pulling or pushing the rod 27 the shaft 6 may be moved in opposite directions, as required, to operate the machine to move the band in forward or backward directions.

29 and 30 indicate guide rollers for the band or ribbon 5, which passes around them and a spacing roller 31 rotatably mounted near the upper roller 3, the circumference of which roller 31 is equal to the depth of the display opening 2. This roller may be of any suitable material but at one end it is provided with a cylindrical member 32 formed of fiber or any other insulating material on which member 32 are mounted three brass cylindrical rings 33, 34 and 35 spaced apart from each other but connected together so as to be in electrical contact with each other, as described later, by a brass bar 36, as shown in Figs. 8, 9 and 11. Ring 33 is continuous as to its peripheral circumference but the peripheral circumference of each of the rings 34 and 35 is broken, that is, these two rings are divided and between the divided ends are inserted vulcanite portions 37 and 38, the portion 37 being of greater length than the portion 38, as shown in Fig. 9. 39, 40 and 41 indicate contact arms secured at one end to a suitable support 42 while at their opposite ends they are provided with suitable adjustable contact screws 43, 44 and 45 adapted to bear respectively on the peripheral surfaces of the rings 33, 34 and 35, and each contact arm is further provided with a terminal, 46, 47 and 48 respectively, to which certain of the electrical circuit wires are connected, as herein-after described.

In order to hold the spacing roller 31 against inadvertent displacement when rotating the rollers 3 and 4, as for instance, when winding or unwinding them by hand when changing bands, a screw 49 is fitted into the side of the casing 1, as shown in Figs. 2 and 10, the casing being indicated by the dotted lines, which screw extends through the side of the casing and is of such length that it may be screwed into a countersunk recess, indicated by the numeral 50, formed in the fibre cylindrical member 32, as shown in Fig. 9, and the relative position of the screw and recess is such that when the screw is seated in the recess holding the roller against movement the contact screws 44 and 45 are centered on their respective vulcanite portions 37 and 38, that is to say, the machine is set for starting.

51 indicates a roller disposed against the band 5 to keep it in contact with the roller 31, which roller 51 is supported in arms 52 and 53 secured to a transverse shaft 54, to which shaft is secured an arm 55 which extends towards one end of the casing, and through the free end of the arm extends a vertical stationary rod 56 on the upper end

of which is mounted a nut 57, between which nut and the arm is disposed a spring 58, from which it will be seen that the spring, bearing down on the arm, maintains the roller 51 in spring contact with the band 5 and the spacing roller 31.

A small electric motor 59 is mounted within the casing 1 and its driving pulley 60 is belt connected to a pulley 61 on a counter-shaft 62 having a worm 63 on one end meshing with a worm wheel 64 secured to a shaft 6 whereby the latter is driven, while towards its opposite end the shaft is provided with a brake drum 65 around which is passed a brake band 66 of any suitable material such as leather, steel, or the like, this band being secured at its lower end, as at 67, while its opposite end is connected to a rod 68 the opposite end of which is connected to a lever 69, which lever is pivotally connected at its lower end to a suitable support 70 while at its upper end it is connected to a lever 71 by an adjusting rod 72, the lever 71 being also pivotally connected at its lower end to the support 70. The rod 72 is extended at the end remote from the lever 71 and to the extended end is connected the end of a tension spring 73 the opposite end of which spring is secured to a stationary bracket 74.

Pivotedly mounted to the lever 71, as at 75, is a metal block 76, shaped in close proximity to the ends of a suitably supported U-shaped yoke 77 which forms a magnet around one of the arms of which yoke is placed a coil 78, as indicated in Fig. 3, and this yoke may be adjusted longitudinally by means of an adjusting screw 79, as shown in Figs. 2 and 3.

The circuit wiring for operating the device is as shown more particularly in Fig. 11 in which the magnet, indicated generally by the numeral 80, the motor 59, the spacing roller 31, the rings 33, 34, 35, and the contact arms 39, 40, 41, are illustrated, it being understood that there is one main circuit common to both the motor and the magnet and used for the operation of both. The circuit wiring is as follows:—81 indicates a bar to which are led five wires, two of them 82 and 83 being the main wires from the source of current and 84, 85 and 86 being switch wires connected to any approved form of switch, which may be the manually operated push button type, as indicated at 87, or it may be a mechanically operated switch, if preferred. Wire 82 is connected direct to the contact arm 39 associated with ring 33, while wire 83 is divided into two branches, one of which 83^a is led to one motor terminal while the other 83^b, is led to one magnet terminal. From contact arm 41 associated with ring 35 a wire 88 extends to the other motor terminal, thus completing the motor circuit wiring,

while from contact arm 40 associated with ring 34 a wire 89 extends to the other magnet terminal, thus completing the magnet circuit wiring. From the switch 87, which has 5 three contacts, the wires 84, 85 and 86 are led to the respective contact arms 39, 40 and 41 so that these wires are therefore in electrical contact with the respective rings 33, 34 and 35 when the switch is closed.

10 The operation is as follows, it being understood that when the machine is stopped the contact screws 44 and 45 of the contact arms 40 and 41 are in contact with the respective vulcanite portions 37 and 38 of the rings 34 15 and 35. To start the machine the switch 87 is momentarily closed so that current passes through wires 85 and 89 to the magnet and wires 86 and 88 to the motor, the magnet and motor circuits being completed through 20 wires 82 and 83, thus energizing the magnet and drawing the levers 71 and 69 back by the attraction of the block 76 to the yoke 77, thus engaging the brake band 66 off the drum 65, and leaving the countershaft 62 free to 25 rotate, which rotation takes place simultaneously with the easing of the brake band, since the motor starts also. The switch is then opened, when the motor continues to run, since although no current passes through 30 wires 84, 85, and 86, it passes from the main wires 82 and 83 to the motor terminals through wires 83^a and 88 to ring 35, and then through the bar 36 to the ring 33 and wire 82, thus making a complete circuit in which 35 the motor is disposed while it passes from the main wires 82 and 83 to the magnet terminals through wires 83^b and 89 to ring 35 and thence through bar 36 to ring 33 and wire 82, thus making a complete circuit in 40 which the magnet is disposed so that the motor continues to run and the magnet remains energized until a revolution of the spacing roller 31 is completed and the insulated portion 37 and 38 carried round into contact 45 with their respective contact screws, when the electrical circuit is immediately broken, the motor circuit first, since the vulcanite portion 38 is longer than the vulcanite portion 37 and thus comes in contact sooner with 50 the contact, thus stopping the motor and de-energizing the magnet, when the spring 73 pulls the levers 69 and 71 in the reverse direction and tightens up the brake band on the drum so that further rotation of the 55 countershaft 62 and spacing roller 31 is im- mediately and positively prevented; until the switch 87 is closed, when the operation just described is repeated.

It will be seen, therefore, that through the 60 operation of the motor the rollers 3 and 4 are also operated thus moving the band past the display opening and as the circumference of the spacing roller is equal to the distance the ribbon travels at each movement it will be 65 seen that the travel of the ribbon is thus auto-

matically and positively controlled without attention on the part of the operator whose only care is to first close the switch 87 and then open it.

What we claim as our invention is:

1. In a street indicator, a casing having a display opening, a band bearing street names, mechanism for moving said band past the display opening including a brake drum, an electric motor for operating said mechanism, a band operated roller having one end provided with three spaced metallic rings in metallic connection with each other, the periphery of each ring being designed to form an electrical current path one continuous and the remaining two interrupted by the insertion therein of a vulcanite portion, a suitably supported contact arm for each ring forming circuit terminals bearing respectively on the continuous path and the interrupted ones, a magnetically operated brake band associated with said brake drum, and an electrical circuit in which said rings, said arms, said motor, and the brake magnet are disposed.

2. In a street indicator, a casing having a display opening, a band bearing street names, mechanism for moving said band past the display opening including a brake drum, an electric motor for operating said mechanism, a band operated roller having one end formed as an electrical circuit terminal, a suitably supported terminal adjacent the band roller terminal, a magnetically operated brake band associated with said brake drum and an electrical circuit in which said motor and the brake magnet are disposed controlled by the band roller terminal.

3. In a street indicator, a casing having a display opening, a band bearing street names, mechanism for moving said band past the display opening, an electric motor for operating said mechanism, a band operated roller having one end provided with spaced metallic rings in metallic connection with each other, the periphery of each ring being designed to form an electrical current path one continuous and the other interrupted by the insertion therein of a vulcanite portion, a suitably supported contact arm for each ring forming circuit terminals bearing respectively on the continuous ring and the interrupted one, and an electrical circuit in which said motor, said rings, and said arms are disposed.

4. In a street indicator, a casing having a display opening, a band bearing street names, mechanism for moving said band past the display opening, an electric motor for operating said mechanism, a band operated roller the circumference of which is equal to the length of the display opening having one end provided with spaced metallic rings in metallic connection with each other, the periphery of each ring being designed to form an electrical current path one continuous and

one interrupted by the insertion therein of a vulcanite portion, a suitably supported contact arm for each ring forming circuit terminals bearing respectively on the continuous one and on the interrupted one, an electrical circuit in which said motor, said rings, and said arms are disposed closed when the arms are in contact with the uninterrupted rings and broken when the contact arm and 10 vulcanite portion are in contact, and means for holding said band operated roller against inadvertent movement when the circuit is broken.

5. In a street indicator, a casing having a 15 display opening, a band bearing street names, mechanism for moving said band past the display opening including a brake drum, an electric motor for operating said mechanism, a band operated roller having 20 one end formed as an electrical circuit terminal, a suitably supported terminal adjacent the band roller terminal, a brake band around said drum, said band being secured at one end and connected at its 25 opposite end to a suitably pivoted arm, an armature pivotally supported on said arm, a magnet the poles of which are disposed in proximity to said armature, a coil associated with said magnet, and an electrical circuit in which said motor, and said 30 coil are disposed controlled by the band roller terminal.

6. In a street indicator, a casing having a display opening, upper and lower rollers 35 therein each adapted to act respectively as a delivery or receiving roller and provided with a key extension on one end, stationary shafts removably mounted in said casing on which said rollers are freely mounted, a 40 sleeve for each roller rotatably mounted on said casing provided at one end with a slot detachably engaging the roller key and at its opposite end with a gear, a rotatable shaft having gears on its opposite ends 45 adapted to co-act with the said sleeve gears, said shaft being longitudinally movable to carry its opposite end gears into or out of engagement with their respective sleeve gears, means for rotating said shaft, and a 50 band bearing street names extending between said upper and lower rollers adapted to be unwound off the one on to the other to pass the display opening by the rotation of the said longitudinally movable shaft.

55. 7. In a street indicator, a casing having a display opening, upper and lower rollers therein each adapted to act respectively as a delivery or receiving roller and provided with a key extension on one end, stationary 60 shafts mounted in said casing on which said rollers are freely mounted, said shafts being divided with one divided portion forming a stationary bearing for the roller and capable of withdrawal out of the roller and 65 the casing, the other divided portion being

rotatably mounted on the casing and fitted with an exterior sleeve having a slot detachably engaging its respective roller key and on its outer end with a gear, a rotatable shaft having gears on its opposite ends 70 adapted to co-act with the said divided shaft gears, said shaft being longitudinally movable to carry the opposite end gears into or out of engagement with their respective divided shaft gears, means for rotating said shaft, and a band bearing street names extending between said upper and lower rollers adapted to be unwound off the one on to the other to pass the display opening by the rotation of the said longitudinally movable 80 shaft.

8. In a street indicator, a casing having a display opening, upper and lower rollers therein each adapted to act respectively as a delivery or receiving roller and provided with a key extension on one end, stationary shafts removably mounted in said casing on which said rollers are freely mounted, a sleeve for each roller rotatably mounted on said casing provided at one end with a slot 90 detachably engaging the roller key and at its opposite end with a gear, a rotatable shaft having gears on its opposite ends adapted to co-act with the said sleeve gears, said shaft being longitudinally movable to 95 carry its opposite end gears into or out of engagement with the sleeve gears and being provided with a worm, a countershaft having a worm gear meshing with said worm, an electric motor, a driving connection between said motor and said countershaft whereby said longitudinally movable shaft is driven by the operation of the motor, and a band bearing street names extending between said upper and lower rollers 100 adapted to be unwound off the one on to the other past the display opening by the rotation of the longitudinally movable shaft.

9. In a street indicator, a casing having a display opening, upper and lower rollers 110 therein each adapted to act respectively as a delivery or receiving roller and provided with a key extension on one end, stationary shafts removably mounted in said casing on which said rollers are freely mounted, a 115 sleeve for each roller rotatably mounted on said casing provided at one end with a slot detachably engaging the roller key and at its opposite end with a gear, a rotatable shaft having gears on its opposite ends 120 adapted to co-act with the said sleeve gears, said shaft being longitudinally movable to carry its opposite end gears into or out of engagement with the sleeve gears and being provided with a worm, a countershaft having a worm gear meshing with said worm, an electric motor, a driving connection between said motor and said countershaft 125 whereby said longitudinally movable shaft is driven by the operation of the motor, a 130

brake drum secured to said countershaft, a
brake band around said drum, electro-magnetic
means for tightening said brake band
on said drum and a band bearing street
names extending between said upper and
lower rollers adapted to be unwound off the
one on to the other past the display opening
by the rotation of the longitudinally movable
shaft.

10 10. In a street indicator, a moveable display element carrying street designations arranged for successive display by movement of the element past a sight opening or its equivalent, motor-driven mechanism
15 for moving the display element, a brake mechanism for stopping movement of the display element, said brake mechanism being adapted to be mechanically operated to set the brake and electro-magnetically to release it, and means operable, after a predetermined movement of the display element, for stopping the motor and permitting coincident mechanical setting of the brake.

11. In a street indicator, a display element
25 carrying street designations arranged to be successively displayed by intermittent movement of the display element past a sight opening or its equivalent, mechanism for moving the display element, an electric
30 motor for driving said mechanism, a normally set brake co-acting with said mechanism, said brake being adapted to be set mechanically to stop operation of the mechanism and released electro-magnetically to permit its operation, a manually operable switch in circuit with the motor and the electro-magnetic brake release means adapted to be momentarily closed to start the motor and permit coincident release of
35 the brake, and means operable to keep the motor and brake release means circuit closed after reopening of the switch while the mechanism moves the display element the predetermined distance, said circuit being
40 then automatically opened to stop the motor and permit coincident mechanical setting of the brake.

12. A street indicator comprising a web having street designations thereon, a pair
50 of winding reels carrying the web, a reel drive mechanism, a motor for driving said mechanism, and a brake mechanism co-acting with the reel drive mechanism, said brake being adapted to be set mechanically coincidently with the stoppage of the motor and released electro-magnetically coincidently with the starting of the motor.

13. A street indicator comprising a web having street designations thereon, means
60 for moving the web, including an electric motor, a brake mechanism co-acting with the said means, said brake being adapted to be set mechanically coincidently with the stoppage of the motor and to be released
65 electro-magnetically coincidently with the

starting of the motor, and means for automatically opening the motor circuit to stop the motor and permit the coincident mechanical setting of the brake when the web has been moved the desired extent.

70 14. In a street indicator, a casing having a display opening, a band bearing street names, motor-driven mechanism for moving said band past the display opening, and a circuit in which said motor is disposed arranged so that when momentarily closed and then opened the motor starts to initially move the band, and means associated with said band adapted to again close the circuit on such initial movement whereby the motor operation is continued to complete the band movement.

75 15. In a street indicator, a casing having a display opening, a band bearing street names, motor-driven mechanism for moving said band past the display opening, a circuit in which said motor is disposed arranged so that when momentarily closed and then opened the motor starts to initially move the band, means associated with said band adapted to again close the circuit on such initial movement whereby the motor operation is continued to complete the band movement, and means for automatically stopping the motor after a predetermined period of operation.

80 16. In a street indicator, a casing having a display opening, a band bearing street names, motor-driven mechanism for moving said band past the display opening, a circuit in which said motor is disposed arranged so that when momentarily closed and then opened the motor starts to initially move the band, means associated with said band adapted to again close the circuit on such initial movement whereby the motor operation is continued to complete the band movement, and means for stopping the motor instantaneously after a predetermined period of rotation.

85 17. In a street indicator, a casing having a display opening, a band bearing street names, motor-driven mechanism for moving said band past the display opening, a motor-starting circuit adapted to be momentarily closed to start the motor and then opened to impart an initial movement to the band, and a normally open motor-operating circuit arranged when closed to continue the operation of the motor after the motor-starting circuit is opened, and means controlled by said band for closing said motor operating circuit.

90 18. In a street indicator, a casing having a display opening, a band bearing street names, motor-driven mechanism for moving said band past the display opening, and a normally open combination motor-starting and motor-operating circuit, the motor-starting circuit being arranged to start the

motor when momentarily closed to initially move the band and the motor-operating circuit to continue the operation of the motor when the motor-starting circuit is opened, 5 said motor-operating circuit including circuit-closing means adapted to be brought into operation through the initial movement of the band.

19. In a street indicator, a casing having 10 a display opening, a band bearing street names, a motor-driven mechanism for moving said band past the display opening, and a normally open combination motor-starting and motor-operating circuit, the motor starting circuit being arranged to start the motor when momentarily closed to initially move the band and the motor-operating circuit to continue the operation of the motor when the motor-starting circuit is opened, said motor- 15 operating circuit including circuit closing means adapted to be brought into operation through the initial movement of the band to then close the circuit and maintain it closed throughout movement of the band past the 20 display opening.

20. In a street indicator, a casing having a display opening, a band bearing street names, a motor-driven mechanism for moving said band past the display opening, and 25 a normally open combination motor-starting and motor-operating circuit, the motor-starting circuit being arranged to start the motor when momentarily closed to initially move the band and the motor-operating circuit to continue the operation of the motor when the motor-starting circuit is opened, said motor-operating circuit including circuit closing means adapted to be brought into operation through the initial movement of the band to 30 close the circuit, said means being also adapted to open the circuit at the termination of the movement of the band past the display opening.

21. In a street indicator, a casing having a display opening, a band bearing street names, a motor-driven mechanism for moving said band past the display opening, and a normally open combination motor-starting and motor-operating circuit, the motor-starting circuit being arranged to start the motor when momentarily closed to initially move the band and the motor-operating circuit to continue the operation of the motor when the motor-starting circuit is opened, 45 said motor-operating circuit including circuit closing means adapted to be brought into operation through the initial movement of the band, said means being adapted to open the circuit automatically at the termination of the movement of the band past 50 the display opening.

22. In a street indicator, a casing having a display opening, a band bearing street names, motor-driven mechanism for moving said band past the display opening, a normally open combination motor-starting and motor-operating circuit, the motor-starting circuit being arranged to start the motor when momentarily closed to initially move the band and the motor-operating circuit to 55 continue the operation of the motor when the motor-starting circuit is opened, and an element disposed in said circuit adapted to be moved by and concurrently with said band a distance equal to the depth of the display opening, said element being adapted on the initial movement of the band to close the motor operating circuit and to open it at the termination of the band movement past 60 the display opening.
